ELECTRICALLY OPERATED FLUID FUEL
BURNER

Walter W. Williams, Philip A. Celander, and Oliver Earl Nesmith, Bloomington, Ill.; said Celander and said Nesmith assignors to Williams Oil-O-Matic Heating Corporation, Bloomington, Ill., a corporation of Illinois

Application December 27, 1932, Serial No. 648,966

4 Claims. (Cl. 137—153)

This invention relates to improvements in electrically operated fluid fuel burners, more particularly to the domestic type which is particularly adapted for installation with the heating plants of homes and buildings.

It is an object of this invention to provide a simple and positive control for the supply of fluid fuel operated by the actuation of the burner mechanism.

With this and other objects in view, reference is made to the accompanying sheets of drawings which illustrate a preferred form of this invention with the understanding that minor detail changes may be made therein without departing from the scope thereof.

In the drawings:

Figure 1 is a view in side elevation of a commercial type of domestic fluid fuel burner with parts broken away, illustrating the air muffler in section and a portion of the oil valve casing in section.

Figure 2 is a view in rear elevation of the fluid fuel burner shown in Figures 1 and 2 with a portion of the fan housing in section and the oil valve casing, metering pump, and a portion of the pressure pump shown in section.

Figure 3 is an enlarged detail view in the central vertical section of the fluid fuel control valve showing the same in closed position.

Figure 4 is a view similar to Figure 3 showing the valve in open position.

The embodiment of this invention is illustrated in connection with a commercial type of fluid fuel burning mechanism for domestic heating purposes of the same general type as illustrated in this applicant Williams' prior patent, No. 1,817,051, granted August 4, 1931, upon electrically operated and controlled oil burning mechanism, and includes a base 1 supported on legs 2 having resilient feet 3, the toes of which mount one end of a leaf spring 4 which is bent back upon itself with the lower free end secured to a pad 5 centrally located thereon by securing means such as shown in Figures 1 and 2. The feet are adjustably secured to the legs 2 by the set screws 6.

In this manner the weight of the burner mechanism upon the base 1 is equally distributed upon the three legs, the outstanding feet carrying the three-point support beyond the confines of the base and increasing the distances of the weight-supporting pads 5 from each other. With the adjustable resilient feet the relation of the burner mechanism to the domestic heater is readily adjusted and such vibration as may be caused by the

operation of the motor and working parts of the mechanism is readily absorbed.

The base 1 supports an integral fan blower casing or housing 7 having an extension 8 for receiving and mounting the electric motor 9. The far side of the motor is provided with a cover or an end bell 10 secured to the casing 8. The motor is provided with a driving shaft 11 for operating an oil pump 12 and also operating a fan blower 13. The driving shaft 11 is extended through the end bell 10 on the opposite side of the motor for operating a compression pump 14 and metering pump 15 mounted upon the end bell. The general construction and operation of the pressure pump and metering pump is of the type disclosed in this applicant Williams' prior patent, No. 1,451,798, granted April 17, 1923.

Figure 2 illustrates an intake pipe 16 leading from a source of liquid fuel supply to the oil pump 12. Figure 1 illustrates an oil pipe 17 leading from the discharge side of the oil pump 12 to an intake 18 of an oil valve casing 19 through which the fluid fuel passes when the motor is operating to the intake side of the metering pump.

Mounted upon the base 1 and extending from the fan housing 7 a draft pipe 20 is provided. Fuel is delivered through a pipe centrally mounted within the draft pipe and terminating in a nozzle adjacent the open end of the draft pipe 20 and continuing in the opposite direction through the lower part of the housing and communicating with a float chamber 23 which in turn communicates by the pipe 24 with the pressure pump 14. This construction in general is disclosed in this applicant Williams' prior patent, No. 1,831,277, granted November 10, 1931, upon a fluid fuel burner construction.

The pressure pump 14 draws atmospheric air into the pump chamber through an air muffler, including a casing 24^a mounted on the casing upon the pressure pump 14, as shown in Figure 1. The casing 24^a is preferably cylindrical in shape with an annular passage-way 25 about a concentric baffle 26. The casing 24^a is provided with a similar shaped cover 27 and a corresponding annular passage-way and corresponding cylindrical baffle. A flexible diaphragm 28 is positioned between the contacting surfaces of the casing 24^a and cover 27, which cover is drawn tightly upon the casing by a plurality of screws 29. This diaphragm is preferably made of a treated heavy flexible paper, such as that commercially known as "Karrapak". The cover 27 is provided with a central opening 30, which supports an air intake tube 31, which passes through

the diaphragm 28 and opens into the casing within the cylindrical baffle 26. The diaphragm is provided with a plurality of apertures 32, which allow the air drawn through the tube 31 to pass from the chamber within the baffle 26 through the diaphragm into the corresponding chamber in the cap. The wall of the cylindrical baffle of the cap is provided with one or more apertures 33, opening into the annular passage-way in the cap and the diaphragm is provided with a plurality of apertures 34, forming a means of communication between the annular passage-ways in the cap and casing. The annular passage-way 25 in the casing is provided with a passage-way 35 leading to the intake 36 of the pressure pump, which passage-way is preferably provided with a ball check valve 37.

As hereinbefore described, the fluid fuel or oil is forced by the oil pump 12, when the motor 20 is operating, through the pipe 17 to the intake 18 of the oil valve casing 19. This oil valve casing is preferably in two parts, of which the lower part 19^a is formed integral with the outer casing 38 surrounding the metering pump 15, as shown 25 in Figures 1 and 2. The lower casing 19^a provides a cylindrical chamber 39, which communicates by the passage-way 40, leading from the bottom thereof through the casing of the pressure pump 14, to the discharge port 41 of the pressure pump, whereby when the pressure is created within the pump, a part of it is transmitted to the chamber 39. A metallic bellows 42, closed at the bottom by the circular plate 43, is mounted upon a metallic annular diaphragm 44, held in place over 30 the chamber 39 by the cap or upper portion of the oil valve casing 19, which is secured to the lower casing by screw threaded bolts 45, as shown in Figures 1 and 2. The upper portion 19 includes chamber 45^a, into which the oil intake 35 18 opens, and which is closed at the bottom by the partition 46. The partition mounts an oil valve seat 47 which is concentric with and depends below the annular diaphragm 44, the seat entering within the metallic bellows 42 and being 40 preferably held in place upon the partition 46 by the screw threaded nut 48. A valve head 49 is normally held seated upon the upper portion of the valve seat 47 by the coil spring 50 surrounding the head 49 and engaging the upper closure or cover 19^b of the casing 19. The valve seat is provided with a cylindrical chamber 51, which opens at the lower end through a plurality of apertures 52 into a passage-way 53 leading through the bottom partition 46 and registering 45 with a similar passage-way 54 in the bottom portion 19^a, which communicates with the metering pump 15, a registering aperture being provided in the diaphragm 44 to provide an unobstructed passage-way from the chamber 45^a through the 50 valve seat 47 and passage-ways 53 and 54 to the metering pump. The valve head 49 is provided with a central depending fluted guide 55, which is received within the chamber 51 of the valve seat and is terminated short of the bottom of the 55 chamber 51 when the head 49 is seated upon the valve seat 47, as shown in the enlarged detailed view Figure 3. The depending screw threaded portion 56 of the valve seat 47 which enters within the bellows 42 mounts a reciprocating valve stem 57 with its lower end resting upon the lower closure of an additional metallic bellows 58, the upper end of which is sealed to the under side of the nut 48. From the above description, it is seen that when the motor is idle 60 75 no pressure is created within the chamber 39 and

the bellows 42 will assume its normal extended position with the valve head 49 seated upon the valve seat 47, thereby closing the communication from the oil pump 12 to the metering pump 15, as shown particularly in Figure 3. When the motor operates the pressure pump, the pressure will be transmitted through the passage-way 40 to the chamber 39, causing the bellows 42 to contract, whereupon the valve stem 57 will engage the guide 55 and move the valve head 49 away from the valve seat 47, as shown in the detailed view Figure 4, so that oil within the chamber 45^a under pressure of the pump 12 will pass between the fluted portion of the guide 55 in the valve seat and through the apertures 52 and passage-ways 53 and 54 into the metering pump 15 as long as the motor is in operation. As soon as the motor stops, the pressure in the casing 44 subsides and the bellows 42 will expand and allow the spring 50 to close the oil valve to the metering 20 pump. In order that the bellows 42 may be caused to contract and expand, a passage-way 59 to the atmosphere is provided in the wall of the upper valve casing 19 and between the partition 46 and annular gasket 44 to the interior of 25 the bellows 42. The additional bellows 58 provides an oil seal for the valve stem 57. In the event that the oil pump 12 supplies oil at a greater rate or higher pressure than can be accommodated by the metering pump, a return 30 pipe 60 to the source of oil supply is connected through the pressure valve 61, of commercial form, with the interior of the chamber within the upper valve casing 19, to form a by-pass, as is 35 customary in such cases.

In the oil valve above described, the spring 50 normally holds the valve seated. When the motor is idle, as the aperture 59 is communicating with the interior of the bellows 42, the bellows is allowed to expand. As soon as the motor 40 begins to operate, the oil pump 12 delivers oil to the interior of the chamber 45 and at the same time the operation of the pressure pump 14 transmits pressure through the duct 40 to the interior of the chamber 39 and, as the pressure increases, the bellows is compressed, thereby transmitting a direct lifting power through the valve stem 57, which directly lifts the valve head 49 from its seat 47, allowing the oil to flow 45 there-through into the metering pump casing. This construction, by providing a direct connection from the interior of the chamber 39 to the interior of the pressure pump through the casing of the pump and chamber, prevents any escape of pressure and is, therefore, more positive 55 in its action. Likewise the pressure within the chamber 39 acts directly and in a straight line to unseat the head 49 of the valve.

When the motor is operating, air is drawn in through the muffler and intake to the pressure 60 pump 14 and at the same time oil is metered into the intake of the pressure pump through the metering pump 15 and both air and oil under pressure are delivered from the pressure pump through the pipe 24 to the float valve casing 23, as shown in Figures 1 and 2.

What we claim is:

1. A valve including a cylindrical valve casing divided into two horizontal chambers, an inlet in the wall of the upper chamber, a valve seat 70 mounted axially upon the dividing wall, an outlet in the dividing wall in connection with the upper chamber through said valve seat, a valve head in the upper chamber normally seating upon said valve seat, a valve actuator within said 75

lower chamber responsive to pressure conditions in said lower chamber to unseat the valve head upon an increase above a predetermined pressure and to seat the valve head upon a reduction of 5 pressure below said predetermined degree, wherein said valve seat includes a sleeve depending therefrom mounted in the division wall and depending therefrom to enter the actuator, and wherein a valve stem is mounted to reciprocate within said sleeve operated by the actuator, and wherein one closed end of a bellows member is secured about the depending portion of the said sleeve and with the bottom of the valve stem contacting the interior of the other closed end 10 of the bellows, said bellows enclosed by said actuator.

2. A valve including a cylindrical valve casting divided into two horizontal chambers, an inlet in the wall of the upper chamber, a valve 20 seat mounted axially upon the dividing wall, an outlet in the dividing wall in connection with the upper chamber through said valve seat, a valve head in the upper chamber normally seating upon said valve seat, a valve actuator within said 25 lower chamber responsive to pressure conditions in said lower chamber to unseat the valve head upon an increase above a predetermined pressure and to seat the valve head upon a reduction of pressure below said predetermined degree, 30 wherein said actuator includes a bellows member concentric to said casting provided with a rigid bottom closure and with the upper walls secured to an annular diaphragm secured to the casing wall, said wall provided with an aperture 35 communicating from the interior of the bellows to the atmosphere.

3. A valve including a cylindrical valve casting divided into two horizontal chambers, an inlet in the wall of the upper chamber, a valve 40 seat mounted axially upon the dividing wall, an outlet in the dividing wall in connection with the upper chamber through said valve seat, a valve head in the upper chamber normally seating upon said valve seat, a valve actuator within 45 said lower chamber responsive to pressure conditions in said lower chamber to unseat the valve head upon an increase above a predetermined

pressure and to seat the valve head upon a reduction of pressure below said predetermined degree, wherein said actuator includes a bellows member concentric to said casting provided with a rigid bottom closure and with the upper walls 5 secured to an annular diaphragm secured to the casing wall, said wall provided with an aperture communicating from the interior of the bellows to the atmosphere, and wherein said valve seat includes a sleeve depending therefrom mounted 10 in the division wall and depending therefrom to enter the actuator, and wherein a valve stem is mounted to reciprocate within said sleeve operated by the actuator.

4. A valve including a cylindrical valve casting divided into two horizontal chambers, an inlet in the wall of the upper chamber, a valve seat mounted axially upon the dividing wall, an outlet in the dividing wall in connection with the upper chamber through said valve seat, a 20 valve head in the upper chamber normally seating upon said valve seat, a valve actuator within said lower chamber responsive to pressure conditions in said lower chamber to unseat the valve head upon an increase above a predetermined 25 pressure and to seat the valve head upon a reduction of pressure below said predetermined degree, wherein said valve seat includes a sleeve depending therefrom mounted in the division wall and depending therefrom to enter the actuator, and wherein a valve stem is mounted 30 to reciprocate within said sleeve operated by the actuator, and wherein one closed end of a bellows member is secured about the depending portion of the said sleeve with the bottom of the 35 valve stem contacting the interior of the other closed end of the bellows, said bellows enclosed by said actuator, and wherein said actuator includes a bellows member concentric to said casting provided with a rigid bottom closure and 40 with the upper walls secured to an annular diaphragm secured to the casing wall, said wall provided with an aperture communicating from the interior of the bellows to the atmosphere.
